UNITED STATES PATENT OFFICE.

PETER C. PATTERSON AND JOHN J. BOAX, OF MCKEESPORT, PENNSYLVANIA.

TUMBLING APPARATUS.

No. 928,399.

Specification of Letters Patent. Patented July 20, 1909.

Application filed November 25, 1907. Serial No. 403,805.

To all whom it may concern:

Be it known that we, PETER C. PATTERSON and JOHN J. BOAX, both of McKeesport, Allegheny county, Pennsylvania, have invented a new and useful Tumbling Apparatus, of which the following is a full, clear, and exact description, reference being had to the accompanying drawings, forming part of this specification, in which—

10 Figure 1 is a top plan view showing one form of our improved apparatus; Fig. 2 is a vertical cross section; and Figs. 3 and 4 are detail views showing different positions of the barrel and lid.

15 Our invention relates to the class of tumbling barrels and is particularly designed for tumbling pipes or tubes though it may be employed for other purposes.

20 The object of the invention is to provide simple and efficient mechanism for feeding the tubes or other material into the barrel, to provide for side charging of the barrel and also to provide mechanical means for closing the lid and discharging the tumbled material.

25 In the drawing 2 represents the tumbling barrel which may be made in sectional form and is provided at its ends with annular bearings 3 which rest upon rollers 4, 4 suitably mounted on the foundation 5. An opening is provided in the side of the barrel which is of the requisite length to receive the pipes or material, this opening being normally closed by lid 6. We have shown the opening as provided with angle irons 7, 7 extending along its side edges; and the door or lid may be hinged to the flanged connections of the barrel sections or otherwise as desired. The barrel may be rotated 30 in any suitable manner as by gear wheel 8 intermeshing with pinion 9 upon shaft 10 having slow motion gearing connection with an electric motor 11. Between the end roller bearings and below the barrel, we provide separate cradles 12 which are shown as consisting of casing with inclined extensions 13 carried on supports 14. These cradles receive the load of tumbled material from the barrel when the lid is opened and the 35 barrel turned over.

40 At one side of the barrel and adjacent thereto is provided a skidway or storage table 15 carried on suitable supporting framing 16 and shown as formed of separate T-rail sections. At the lower ends of certain of these T-rails are pivoted the swing-

45 arms 17 which extend beyond the rails and to a point adjacent to the barrel surface. We have shown fillers as secured to opposite sides of the rail webs, the arms being pivoted through these fillers and through the rail and a roller 18 is preferably positioned between the two side pieces of each swinging arm. Upon a shaft 19 extending lengthwise 50 of the storage table or skidway are placed star wheels 20 which may be provided with 55 projecting arms; and the shaft 19 is connected through slow motion gearing 21 and 60 22 with an electric motor 23.

65 In the use of the apparatus the pipe or 70 other material to be tumbled is fed upon the storage table and rests against the arms of the star wheels as shown in Fig. 2. When 75 it is desired to stop the barrel it is brought to the position shown in Fig. 3 with the lid 80 open by rotating it in a clockwise manner. The shaft 19 is then turned slowly by actuating the motor 23 and the star wheels are 85 turned far enough to allow the load between two of the arms to roll down the skidway 90 from the swing arms and into the barrel through the side opening. The barrel is then 95 rotated slowly until the lid or door lifts the swinging arms and passes upwardly beyond them. The arms then drop back against the 100 lower stops 24 and the rotation of the barrel is then reversed in a counter-clockwise direction as shown in Fig. 4, by which action the swinging arms close the lid. A slight rotation will effect this and the lid is then secured by bolts or any suitable securing device. The barrel is then rotated in the ordinary manner, preferably in a counter-clockwise direction, until the tumbling is completed. It is stopped with the lid uppermost 105 and the lid fastening is then detached when the barrel is rotated half way around in a clockwise direction, thus allowing the pipes, scale, etc., to drop out into the cradle. The barrel is then turned into the position shown 110 in Fig. 3 and the operation is repeated.

115 The advantages of our invention will be apparent to those skilled in the art. The end feeding of the barrel by hand is done away with and a proper load is picked up and fed automatically into the barrel at each partial turn of the star wheels. The lid is closed by the rotation of the machine in conjunction with the swinging arms and the barrel is self cleaning, as both the material to be cleaned and the scale and dirt drop out when the barrel is turned upside down. The

load may be easily lifted from the cradle by an overhead crane or other suitable mechanism. Many other changes may be made in the form and arrangement of the barrel driving mechanism also in the storage table and feeding means, without departing from our invention.

We claim:

1. In apparatus for tumbling pipes and similar articles, the combination with a tumbling barrel having an inlet and outlet opening in its side and a storage rack extending alongside the barrel, of mechanism arranged to transfer a predetermined number of the pipes on the rack into the barrel; substantially as described.
2. In apparatus for tumbling pipes and similar articles the combination with a rotary tumbling barrel having an inlet and outlet opening in its side and an inclined storage rack alongside the barrel, of a star wheel feeding mechanism arranged to select and transfer a predetermined load of pipes from said rack into said barrel; substantially as described.
3. The combination with a tumbling barrel having a side opening, of an inclined storage rack extending along side thereof and a star wheel feed device arranged to deposit successive loads in the barrel; substantially as described.
4. A tumbling barrel having a side opening, a hinged closure therefor, and mechanism arranged to turn the closure into its closing position when the barrel is rotated in one direction, and to permit rotation of the barrel in the opposite direction with the closure in its open position; substantially as described.
5. The combination with a tumbling barrel having a side opening, of a pivoted lid therefor and a closing device in the path of the lid when open and arranged to close the lid when the barrel is turned in one direction, said closing device being arranged to move out of the path of the open lid when the barrel is turned in the opposite direction; substantially as described.

6. The combination with a tumbling barrel having a side opening, of a swinging closure for the opening, a storage rack extending along side the barrel and a projecting arm on the rack arranged to close the lid when the barrel is turned; substantially as described.

7. The combination with a tumbling barrel having a side opening and lid, of a rack extending along side the barrel and having pivoted arms with stops to prevent their movement in one direction; substantially as described.

8. In apparatus for tumbling pipes and similar articles the combination with a tumbling barrel having an inlet and outlet opening in its side and a hinged lid for closing said opening, of an inclined rack alongside the barrel and swinging arms pivoted on the rack, said arms being arranged to engage with and close the lid when said barrel is rotated; substantially as described.

9. In apparatus for tumbling pipes and similar articles a rotary tumbling barrel having a side inlet and outlet opening and a cradle arranged under the barrel, with their axes in substantially parallel lines said cradle being adapted to receive and assemble pipes discharged from the barrel; substantially as described.

10. In apparatus for tumbling pipes and similar articles, a rotatable barrel having a side inlet and outlet opening, means for rotating the barrel, a storage rack for the pipes, means for feeding a predetermined load from the rack into the barrel and a cradle upon which the pipes delivered from the barrel are deposited and assembled in position to be removed from the cradle; substantially as described.

In testimony whereof, we have hereunto set our hands:

PETER C. PATTERSON.
JOHN J. BOAX.
